WITNESS:

UNITED STATES PATENT OFFICE.

GIBBONS J. DENNIS, OF KIEFER, OKLAHOMA.

CLAMP FOR TANKS.

Application filed December 2, 1922. Serial No. 604,529.

To all whom it may concern.

Be it known that I, GIBBONS J. DENNIS, a citizen of the United States, residing at Kiefer, in the county of Creek and State of Oklahoma, have invented new and useful Improvements in Clamps for Tanks, of which the following is a specification.

This invention relates to clamping devices and has for its object the provision of a novel base and means associated therewith for effectually clamping a tank thereonto, the construction and arrangement being such as to insure maximum simplicity, ease of operation and economy of construction.

With the above and other objects and advantages in view the invention consists in the details of construction to be hereinafter more fully described and claimed and illustrated in the accompanying drawings, in which:

Figure 1 is a plan view of the device holding a tank, the tank being in section,

Figure 2 is a vertical section,

Figure 3 is a perspective view of one of the clamping members.

Referring more particularly to the drawing the letter A designates an upright cylindrical tank which is here illustrated as being constructed of metal and which is provided at its bottom edge with an outwardly extending flange B.

In carrying out my invention I provide for the tank a bottom 10 which is here shown as formed of wooden bars or slats 11 arranged in edge to edge relation so as to be leak proof. The slats forming this bottom are of sufficient length to project to quite a considerable extent beyond the flange B at the lower edge of the tank and the ends of the slats are curved so that they will co-operate to define a circular periphery which is concentric with the tank. I also provide a plurality of binding members 12 which are of metal and which are arcuate in shape the curvature being such that they will conformingly engage upon the periphery of the wooden bottom. These binding members are arranged in somewhat spaced relation as shown and their clamping action with respect to the bottom is effected by means of a hoop 13 which seats within a plurality of notched lugs 14 projecting outwardly from

the binding members. One end of this hoop is formed with a lateral ear 15 which receives the other end, and this other end is threaded as shown for carrying a clamping nut 16, which, when turned up will operate to contract the hoop and bind the members 12 against the bottom.

For securing the tank upon this bottom, I provide a plurality of clamping plates 17 arranged about the periphery of the tank and having one end bearing upon the bottom 10 and their other ends engaging upon the flange B. These clamping plates are formed with elongated slots 18 through which pass bolts 19 extending upwardly through the bottom and carrying nuts 20.

From the foregoing description and a study of the drawings it will be obvious that the tank may be quickly and easily secured in position and that the device will operate to hold it rigidly and prevent any possible displacement. Owing to the simplicity of the construction and the fewness of the parts it is apparent that there is nothing to get out of order so that the device should have a long life and satisfactorily perform all of its functions.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. In combination, a base, a tank mounted thereon and formed at its lower edge with an outwardly extending flange seated upon the base, a plurality of clamping plates arranged in circumferential series and bearing upon the base and upon said flange, said clamping plates being formed with slots extending radially with respect to the center of the base, and bolts passing through the base and through said slots.

2. In combination, a base, a tank mounted thereon and having an outwardly extending flange seated upon the base, and a plurality of clamping plates arranged in circumferential series and adjustably mounted upon the

base for movement radially of the base, said clamping plates having their outer edges bearing upon the base and their inner edges bearing upon said flange.

5 3. In combination, a base, a tank mounted thereon and provided at its lower edge with an outwardly extending flange seated upon

the base, a plurality of clamping plates arranged in circumferential series and bearing upon the base and upon said flange, and 10 bolts passing through the base and through said clamping members.

In testimony whereof I affix my signature.

GIBBONS J. DENNIS.
